UNITED STATES PATENT OFFICE.

HENRY BERGER, OF NEW YORK, N. Y.

DESIGN FOR CENTER-PIECE.

Specification forming part of Design No. **11,327**, dated August 12, 1879; application filed July 2, 1879.
[Term of patent 7 years.]

To all whom it may concern:

Be it known that I, HENRY BERGER, of the city, county, and State of New York, have originated a new Design for Center-Piece, of which the following is a full, clear, and exact description, reference being had to the accompanying photograph, which represents a face view of my design.

My design consists in a central shield formed of a rosette and a circular bead, which is fringed with scallops, in combination with a panel surrounding said shield, and which is ornamented by a wreath of foliage, and with a circular border composed of a series of foils, segments, and arabesques, whereby I obtain a design presenting a handsome and distinguishing appearance.

In the photographic illustration, the letter A designates a rosette, and B is a circular bead, fringed with scallops C, composing the central figure or shield of my design. D is a panel surrounding said central bead, and containing a wreath, E, of foliage, the same consisting of stems carrying leaves and berries. Said panel D is inclosed by a circular border composed of

foils F, segments G, and arabesques H, the foils being united by said segments, and the arabesques being interposed between the foils, as shown. Each of the foils F is ornamented by a button, I, situated in the central portion thereof.

What I claim as new, and desire to secure by Letters Patent, is—

The design for a center-piece, consisting of a central shield formed of a rosette, A, and a circular bead, B, which is fringed with scallops, in combination with a panel, D, surrounding said shield, and which is ornamented by a wreath, E, of foliage, and with a circular border composed of foils F, segments G, and arabesques H, substantially as shown and described.

In testimony that I claim the foregoing I have hereunto set my hand and seal this 16th day of July, 1877.

HENRY BERGER. [L. S.]
